(57) **CLAIM**

The ornamental design for a bug toy, as shown and described.

DESCRIPTION

FIG. 1 is a front, perspective view of a bug toy showing our new design;

FIG. 2 is a front view thereof;

FIG. 3 is a rear view thereof;

FIG. 4 is a right side view thereof;

FIG. 5 is a left side view thereof; and,

FIG. 6 is a top view thereof.

FIG. 7 is a front, perspective view of the bug toy of FIG. 1 illustrated with additional environmental subject matter;

FIG. 8 is a front view thereof;

FIG. 9 is a rear view thereof;

FIG. 10 is a right side view thereof;

FIG. 11 is a left side view thereof; and,

FIG. 12 is a top view thereof.

In the drawings, the broken lines depict environmental subject matter only and form no part of the claimed design. The bottom views of the bug toy have been omitted because the bottom surfaces form no part of the claimed design.
